UNITED STATES PATENT OFFICE.

HARRY F. JOSEPH, OF DAVENPORT, IOWA, ASSIGNOR TO MICRO MACHINE COMPANY,
OF BETTENDORF, IOWA, A CORPORATION OF IOWA.

PROCESS OF GRINDING.

Original application filed May 15, 1923, Serial No. 639,141. Divided and this application filed August 17, 1923. Serial No. 657,891.

To all whom it may concern:

Be it known that I, HARRY F. JOSEPH, a citizen of the United States, residing at Davenport, in the county of Scott and State of Iowa, have invented certain new and useful Improvements in Processes of Grinding, of which the following is a full, clear, and exact description, reference being had to the accompanying drawings.

10 This invention relates to a method of wet grinding and more particularly to a method for the internal grinding of cylinders and the like.

15 This application is a division of applicant's copending application Serial No. 639,141, filed May 15, 1923.

An object of the invention is to provide a process for grinding in which a liquid is used to forcibly wash the sediment and 20 grindings from the sides of the cylinder and carry them out, so that a clean surface of the metal is always presented to the grinding wheel, and also to cool the surface to be ground.

25 A further object of the invention is to provide means whereby the surface of the cylinder is washed continuously and progressively in front of the contacting portion of the wheel and cylinder, so that a supply of liquid is present to be carried between the wheel and the work in order to 30 improve the quality of surface as is well known with wet grinding.

35 In the grinding of cylinders internally it is customary to rotate a suitable spindle carrying a grinding wheel at the proper speed so that the speed between the contacting portion of the wheel and the cylinder is suitable for the character of the 40 work and wheel, as is well understood in the art. In addition, the wheel is smaller in diameter than the work and the spindle is mounted eccentrically in a drum to give it a movement in an orbital path around the 45 work so that only a small portion of the wheel and work are in actual contact at any one instant and the contacting portion moves in a cylindrical path around the inside of the cylinder. In addition to these 50 movements, the cylinder or the spindle is moved longitudinally one with respect to the other, so that for a given setting a uniform amount of material may be removed throughout the length of the cylinder.

In carrying out my process it is desirable 55 to project liquid against the cylindrical wall to be ground preferably in the circumferential path of the grinding wheel so that the surface of the metal just ahead of the contacting portion of the wheel and cylindrical 60 wall will always be clean.

These and other objects will be apparent from the following description and annexed drawings, in which

Figure 1 is a vertical longitudinal section 65 taken through the spindle and the operating mechanism.

Fig. 2 is a fragmentary section of the spindle within a cylinder.

Fig. 3 is a section on line 3—3, Fig. 2, 70 showing the baffle construction.

Fig. 4 is a diagrammatic view through 75 the cylinder showing the spindle, arrows diagrammatically indicating the direction of the liquid in the cylinder.

The invention is shown in connection with a machine for internal grinding of the general type shown in my Patent Number 1,396,123. The machine frame or support *a* has a cylindrical portion *b* in which is 80 rotatably mounted the drum *c*. The drum *c* has an external gear *d* in mesh with the gear *e* of the drive shaft *f* and is thereby constantly rotated. Journaled in the drum *c* is an eccentric sleeve member *g* having a 85 worm wheel *h* fixed to one end which meshes with a worm *j* carried by the drum. A tubular spindle housing *k* is rigidly secured within an eccentric bore in the ends of the sleeve *g* and extends parallel with the axis 90 thereof. The sleeve member *g* may be adjusted by the worm *j* to vary the eccentricity of the spindle housing *k* with respect to the drum. Within the spindle housing *k* is a tubular spindle *l* preferably composed of a 95 plurality of sections independently mounted for rotation therein. The spindle *l* is driven through the pulley *m* by any suitable driving means (not shown).

With this mechanism the spindle housing 100 is given an orbital movement and the spindle is independently rotated within the housing, as is commonly understood in the art.

It is also common to cause a relative 105 longitudinal movement between the grinding wheel and the work and one method consists in mounting the work upon a mov-

able table which is reciprocated forward and backward with respect to the grinding wheel (an example of which is shown in my previously mentioned patent). Another 5 method comprises mounting the grinding wheel spindle and its operating mechanism on a reciprocating mechanism. My process may be carried out by either of these constructions (not shown), it being only necessary that there be a relative longitudinal movement between the work and the grinding 10 wheel.

The spindle 7 is hollow, having a passage 3 therethrough for conducting liquid 15 to the grinding wheel 4. The protective cap 5 is secured to turn with the spindle 7 and receives on its hub 5' the grinding wheel 4. The wheel is securely clamped to the spindle to turn therewith by a nut 6 which is located 20 within the recessed portion of the wheel 7. The nut 6 has radial passages or ducts 8 therethrough, the inner ends of which are in communication with the spindle 3 so that liquid coming through the 25 spindle is discharged into the ducts and the outer portion of the nut acts as a disk or baffle to direct the liquid radially outwardly against the annular wall of the grinding wheel surrounding the recess. When the 30 spindle is rotated, the liquid flows across the face of the wheel from the recess and is projected radially against the work.

Due to the angular velocity of the wheel and baffle, the liquid is caused to move rapidly 35 in such direction as to strike the cylinder wall and spread axially so that it forcibly washes the surface of the cylinder. However, in normal cylinder grinding the velocity 40 of the grinding wheel is relatively so high compared to the orbital movement of the wheel that the liquid is caused to flow around the surface of the cylinder at a velocity many times greater than that of the orbital movement of the wheel. The surface, 45 therefore, of the work just in front of the path of the contacting portion of the wheel and work is thoroughly washed clean. Also, fresh, clean liquid is present just behind 50 the wheel ready to be carried by the cutting surface of the wheel across the work, thus enabling the wheel to produce the improved quality of surface generally known to be obtained by wet grinding as frequently used for grinding the outside or external 55 surfaces of objects.

As the liquid is projected with such force and velocity against the surface of the work, it continually forms a rotating, layer of liquid which rotates around the cylinder in 60 the same direction as the orbital movement of the wheel. The constant stream of liquid at high velocity also causes the liquid already rotating around the cylinder to be forced outwardly in both directions from 65 the portions where the liquid first contacts

with the cylinder wall, thus ensuring the liquid, which has picked up accumulated sediment and grindings therein, being forced outwardly in both directions from the cylinder and preventing its coming in the progressive path of the wheel to "load" the wheel or cause loose particles to be carried by the wheel around the cylinder and to impair the surface of the work. The incoming clean liquid thus spreads and flows outwardly along the cylinder wall and transversely across the spiral path of the contacting portion of the grinding wheel and cylinder wall, keeping the cylinder wall clean for the grinding action of the wheel. 70 75 80

It will thus be seen that my process can be carried out by various means and in various ways. It seems essential, however, that the liquid be projected against the surface of the cylinder so that it is present in sufficient quantity behind the wheel so that it can be carried along with the wheel to the contacting portion of the wheel and work. In the present disclosure the liquid is so present behind the wheel, due to the fact that the relatively high velocity imparted to it either by the wheel or the baffle or a combination of the two, causes it to strike the cylinder wall and rotate as a sheet or layer around the periphery of the cylinder. 90 95

Any suitable liquid such as water or cutting compound may be used, it being desirable, of course, to select a liquid which will assist and preserve the cutting action of the wheel and will assist the production of a relatively smooth surface, which is characteristic of wet grinding. 100

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims. 105 110 115

What I claim is:

1. The process of grinding a cylindrical internal recess which comprises rotating a spindle carrying a grinding wheel in said recess, causing a relative orbital and longitudinal movement between the wheel and cylinder, and causing a layer of liquid to move with a relatively higher speed around said cylinder in the same direction as said relative orbital movement and to spread transversely across the orbital path of the wheel. 120 125

2. The process of grinding a cylindrical internal recess which comprises rotating a spindle carrying a grinding wheel in said recess, causing a relative orbital and longitudinal movement between the wheel and cylinder, and causing a layer of liquid to move around said cylinder in the same direction as said relative orbital movement 130

and at a speed relatively higher than said orbital movement, and to forcibly spread transversely across the path of the contacting portion of the grinding wheel and the wall of the recess.

3. The process of grinding cylinders which comprises rotating a spindle carrying a grinding wheel at a relatively high speed in said cylinder, causing a relatively slow

10 orbital and longitudinal movement between the wheel and the cylinder, forcing liquid along the spindle, deflecting said liquid against said cylinder walls and causing said liquid to move at a relatively high speed 15 around said cylinder and spread transversely across the path of the grinding wheel, whereby the surface of said cylinder is continuously washed with clean liquid and liquid is supplied for assisting the grinding.

20 4. The process of internal grinding which comprises rotating a hollow spindle carrying a grinding wheel in said cylinder, causing a relative orbital movement between the wheel and cylinder and eccentric to the axis 25 of the grinding wheel, causing relative longitudinal movement between the wheel and cylinder, forcing liquid through said spindle to the grinding wheel and deflecting the liquid so that it is projected by said wheel 30 with a relatively high velocity around the cylinder wall substantially in a plane through the wheel.

5. The process of grinding a cylindrical internal recess which comprises rotating in

a cylinder a spindle carrying a grinding wheel, bodily rotating the spindle in said cylinder, whereby a relative orbital movement between the grinding wheel and cylinder is obtained, reciprocating said cylinder longitudinally of said spindle, whereby a relative longitudinal movement between the grinding wheel and cylinder is obtained, and forcibly projecting liquid against the internal surface of the cylinder in the same direction as said relative orbital movement and in a plane substantially parallel to the plane of the grinding wheel, and whereby said liquid is caused to progressively spread transversely across the orbital path of the wheel.

6. The process of grinding a cylindrical internal recess which comprises rotating on its own axis in a cylinder a spindle carrying a grinding wheel, bodily rotating the spindle in said cylinder to cause an orbital movement in said cylinder, reciprocating said cylinder with respect to said grinding wheel and projecting liquid at a relatively high velocity in the same direction as said bodily rotation of said spindle and against the cylindrical face of the work, whereby said liquid is caused to progressively spread transversely across the path of the contacting portions of the grinding wheel and the work.

In testimony whereof, I hereunto affix my signature.

HARRY F. JOSEPH.
